UNITED STATES PATENT OFFICE.

ESTYN M. CHARLES, OF GOLDEN, COLORADO.

MECHANICAL SHOVEL.

Application filed January 18, 1926. Serial No. 81,960.

This invention relates to improvements in mechanical shovels of the type in which the digging element and the power unit are widely separated.

In the mining of coal and other places where a large amount of material such as coal, ore or muck must be removed, the need of a mechanical apparatus for loading the same onto the mine cars for removal has long been felt and many devices have been invented for this purpose, most of which, however, are very complicated and expensive.

It is the object of this invention to produce a mechanical shoveling device of simple construction that can be attached to the mine car and which can be operated from a source of power located some distance away from the shovel.

It is a further object of this invention to produce a shoveling device of such light weight that it can be handled by two men and which can be readily removed from or applied in place on a mine car.

My invention can be best described and will be most readily understood when reference is had to the accompanying drawings in which the preferred embodiment has been illustrated and in which:

Fig. 1 is a side elevation of my device showing the several parts assembled in operative relation;

Fig. 2 is a section taken on line 2—2, Fig. 1;

Fig. 3 is a section taken on line 3—3, Fig. 2;

Fig. 4 is a section taken on line 4—4, Fig. 2;

Fig. 5 is a side elevation of the shoveling mechanism showing also how this is attached to the front wall of the car;

Fig. 6 is a plan view looking down upon the shoveling mechanism illustrated in Fig. 5;

Fig. 7 is a section taken on line 7—7, Fig. 6;

Fig. 8 is a section taken on line 8—8, Fig. 1;

Fig. 9 is a section to an enlarged scale taken on line 9—9, Fig. 1; and

Fig. 10 is a section taken on line 10—10, Fig. 6.

As my invention is primarily designed for use in coal mines, I have illustrated the same as employed in this relation. Numeral 1 represents the floor and numeral 2 the roof

of a coal mine while 3 represents a pile of broken coal that is to be loaded into the pit car 4 which rests on the rails 5 of the mine track. Secured to the upper edge of the front wall 6 of the pit car is my improved shoveling apparatus whose construction is best shown in Figs. 5, 6 and 7 and which is constructed as follows: A head frame consisting of two parallel bars 7 and 7^a having downwardly extending arms 8 and 8^a is secured to the front wall of the pit car 6 by means of the angular bracket arms 9 and 9^a whose upper ends are connected with the arms 8 and 8^a by means of rivets 10. The arms 8 are connected by means of a flat bar 11 whose ends 12 are attached to the arms by means of bolts or rivets 13 (Fig. 10). The lower ends of the arms 8 are provided with clamping screws 14 (Fig. 5) which serve to hold the frame rigidly in place. Secured to the inside of the arms 8 and 8^a are lugs 15 which carry projecting pins 16 that serve as pivots for the lower end of the bars 17 and 17^a which are held from withdrawal therefrom by means of the washers 18. A guy wire 19 is secured to the other end of each of the bars 7 and 7^a and have their other ends anchored to the opposite end of the car at the point indicated by numeral 20. Secured to the upper end of each bar 7 and 7^a is a pulley 21 whose function will hereinafter appear, while similar pulleys 22 are secured to the free ends of bars 17 and 17^a. The pulleys 22 are enclosed within a guide frame 23. A chute having a bottom 24 and sides 25 and 26 is slidably connected to the bars 17 and 17^a by means of Z bars 27 that are secured to the sides 25 and 26 by means of rivets 28. The forward ends of the sides 25 are somewhat tapered in the manner shown in Fig. 7 and the bottom curved upwardly. Secured to the front edge of the bottom 24 is a shoe 29 carrying a roller 30 that is adapted to roll along the floor. The rear ends of sides 25 and 26 are provided with slots 31 that receive the ring or washer 18 when the conveyor is in the position shown in Fig. 5. Cables 32 pass over the pulleys 21 and are anchored at 33 (Fig. 5) near the front end of the chute. Other cables 34 pass between the pulleys 22, thence along the bars 17 and 17^a to and about the pulleys 21 and have their ends anchored at 36 near the rear end of the chute. It is evident that when the cables 32 are moved rearwardly in the direc-

tion of the arrow in Fig. 5 that the chute will be raised and that if they are permitted to move in the opposite direction the chute will move downwardly towards the position shown in Fig. 1. When the roller 30 rests upon the floor, then if cables 34 are moved rearwardly, the chute will be moved forwardly in a manner quite evident when the arrangement shown in Fig. 5 is considered.

Let us now assume a case in which the cables 34 are held against movement and in which the parts are in the position shown in Fig. 1. If sufficient force is applied to the cables 32, the chute will be raised towards the position shown in Fig. 5 and will raise a considerable load of coal. It is evident from Fig. 1 that the tension in cables 32 can be resolved into two components one of which tends to lift the chute and the other of which tends to move it rearwardly, therefore, if the cables 34 are permitted to yield the chute will slide rearwardly as it is raised until it finally reaches the position shown in Fig. 5 when the coal will slide into the car. After the chute has deposited its load, the cable 32 may be released slowly so as to allow the chute to move downwardly until the roller 30 rests upon the floor when force is applied to cables 34 for extending the chute to the position shown in Fig. 1. By repeating this cycle coal will be transferred from the pile 3 to the pit car.

Let us now describe the apparatus by means of which the shoveling apparatus is manipulated. A frame comprising two spaced base members 37 that are held in parallel relation by means of uprights 39 supports an electric motor 40 or any other prime mover. A worm gear 41 is provided with an axle 42 that is journaled in the bearings 43 which are secured to the underside of the beams 38. A worm 44 is fastened to the shaft 45 which in turn is rotated by means of the motor so that when the motor operates the worm gear 41 will rotate. The worm gear 41 may be enclosed in a casing 46. Secured to the shaft 42, one on each side of the housing 46, are cams 47 and 48 which are respectively the crowding and the lifting cams. A lever 49 has its lower end pivoted at 50 and carries a roller 51 whose surface engages the outer edge of the cam 47. Secured to the upper end of lever 49 is a spring 52 to which is secured a pulley 53. A cable 54 has one end connected with the cables 34 and after passing about the pulley 53 has its other end anchored to one of the uprights 39 at 55. Operatively associated with the lifting cam 48 is a lever 56 that is pivoted at 57 and carries a roller 58 that engages the outer periphery of the cam 48 in the manner shown in Fig. 4. Connected to the lever 56 near its upper end is a pulley 59 about which the cables 32 pass. The ends of

these cables are anchored at 60 to the uprights 39. The cams 47 and 48 are related to each other in a certain way which will now be described. The lifting cam 48 must be so constructed that if we begin with the parts as shown in Fig. 1, it will impart to the lever 56 a rearward motion that raises the chute to the position shown in Fig. 5. The chute should then be held stationary for a short time so as to permit the load to be emptied into the car; the lever 56 should now move forwardly until the front end of the chute rests upon the floor and to give sufficient slack to permit the chute to be fully extended to the position shown in Fig. 1. Let us now consider the cam 47. When the parts are in the position shown in Fig. 1, the lever 49 occupies its rearmost position. As the chute is being lifted the lever 49 is permitted to move forwardly so as to allow the two parts of which the chute is constructed to move to the position shown in Fig. 5, it should then be held stationary until the end of the chute has come into contact with the floor, when it is caused to move rearwardly and thereby extend the chute to its maximum forward position. The exact configuration of the cams has not been given for the reason that it depends on so many variables that the exact contour of each cam can only be determined after the design of the machine has been fully established. The shapes of the cams as shown on the drawings are, however, substantially correct.

It will be noted that a spring 52 has been inserted between the lever 49 and the cable 54. The purpose of this spring is to prevent the breakage in case the end of the chute strikes some obstruction.

I desire to call particular attention to the fact that the digging or shoveling unit is separated from the power unit and that the two are connected by means of the flexible cables only. This makes it possible to extend the distance between the shoveling unit and the power unit to any desired extent by merely lengthening the cables.

When the pit car is filled, the operator removes the shoveling mechanism and attaches it to the empty car that is substituted for the filled one. The cars are, of course, anchored to the track during the loading operation. This may be accomplished in any suitable manner.

Having now described my invention, what I claim as new is:

1. A shoveling and loading device for loading material into a car, comprising, in combination, a head frame adapted to be secured to the sides of a car, a shoveling and elevating mechanism comprising two telescopically connected members, one of which has one end pivotally connected with the head frame, means for extending said mem-

bers, and means for oscillating said members about the pivot.

2. A shoveling and loading device for loading material into a car, comprising, in combination, a head frame adapted to be secured to the sides of a car, a shoveling and elevating mechanism comprising two telescopically connected members, one of which has one end pivotally connected with the head frame, means for extending said members, means for raising the free ends of said members and for simultaneously contracting them, means for lowering the free ends and means for extending said members.

15 3. A shoveling and loading device for loading material into a car, comprising, in combination, a head frame adapted to be secured to the sides of a car, said head frame having two upwardly and forwardly extending arms, a pulley secured to the free end of each arm, a two part shoveling and elevating mechanism pivotally connected with said head frame, the two parts of said mechanism being telescopically connected with each 20 other, means comprising a cam for extending said members, means comprising a second

cam and cables that pass over the pulley of the head frame for raising said shoveling members, means for permitting the shoveling members to be collapsed as they are 30 raised and means for lowering said shoveling members while collapsed.

4. A device for elevating material from a supporting surface and for transferring the same to a receptacle located at a higher level 35 than the supporting surface, comprising, in combination, a two part telescoping shoveling and elevating device, one end of said device being pivoted at a point above said receptacle, the other end being adapted to rest 40 upon the supporting surface, means for extending said device while the end rests on the surface, means for raising the free end of said device into a position higher than the pivot, means for permitting the parts of 45 said device to be collapsed while they are being raised, and means for lowering said device until its free end rests upon the supporting surface.

In testimony whereof I affix my signature.

IESTYN M. CHARLES.
